(57) **CLAIM**

The ornamental design for a pet collar, as shown and described.

DESCRIPTION

FIG. 1 is a perspective view of a pet collar, shown closed in a first configuration.

FIG. 2 is a front view of the pet collar of FIG. 1.

FIG. 3 is a rear view of the pet collar of FIG. 1.

FIG. 4 is a left side view of the pet collar of FIG. 1.

FIG. 5 is a right side view of the pet collar of FIG. 1.

FIG. 6 is a top view of the pet collar of FIG. 1.

FIG. 7 is a bottom view of the pet collar of FIG. 1; and, FIG. 8 is a top view of the pet collar of FIG. 1, shown open and flattened in a second configuration.

Any shade lines are not features of the claimed design but are utilized to illustrate the surface contours of the pet collar design in the drawings.

1 Claim, 8 Drawing Sheets
